UNITED STATES PATENT OFFICE

CHARLES A. ROBINSON, OF SALEM, MASSACHUSETTS, ASSIGNOR TO UNITED SHOE MACHINERY CORPORATION, OF PATERSON, NEW JERSEY, A CORPORATION OF NEW JERSEY

MACHINE FOR SHAPING UPPERS OVER LASTS

Application filed May 20, 1931. Serial No. 538,771.

This invention relates to machines for use in the manufacture of boots and shoes for shaping uppers over lasts, and more particularly to machines having means for gripping and pulling the upper in the upper-shaping operation. The invention is herein illustrated as applied to a lasting machine of that type in which a gripper is provided for gripping and pulling the upper successively in different locations along the edge of the shoe bottom as the shoe is presented and held by the operator in different positions, but it is to be understood that in its more general aspects the invention is not limited to machines of that particular type.

Machines of the above-mentioned type, as commonly constructed, comprise in their organization means including a spring for imparting to the gripper yieldingly upper-pulling or "updraw" movement heightwise of the last, spring means for thereafter imparting to the gripper overdraw movement to carry the marginal portion of the upper inwardly over the bottom of the last, and means for laying the marginal portion of the upper over and upon the outer face of a sole or insole on the last while the upper is held under tension by the gripper. It is desirable that the upper be subjected to a strong pull heightwise of the last in order to stretch it and conform it properly to the contour of the last. It is, however, desirable that the force with which the gripper is urged thereafter in the direction of the pull shall not be so great as to prevent the overdraw spring from moving the gripper well inwardly over the bottom of the last or so great that the upper is subjected to undue strain by the overlaying means in laying it over the sole or insole. If the strain on the upper is unduly great in the overlaying operation it may be difficult under some conditions for the operator to control the shoe in such manner as to prevent its lateral displacement, and if the shoe has an insole provided with a lip in engagement with the sole rest with which machines of this type are provided there may be danger, in operating on some work, of distortion of the lip by the lateral pressure of the sole rest against it.

Furthermore, under force tending to move the gripper heightwise of the last may prevent the gripper from being readily drawn more or less toward the bottom of the last by the pull of the upper thereon in the overlaying operation, as is usually necessary if it is to maintain control of the upper substantially until the end of that operation.

In view of the above and other considerations, it is an object of the present invention to provide improved means for operating and controlling the gripper in such manner that the upper may be subjected to a pull of the force required for the best results in stretching and conforming it to the contour of the last, and yet will not be subjected thereafter to such strain as to prevent the overdraw and overlaying operations from being performed in the most satisfactory manner and without undesirable results of the character above mentioned. For the purpose in view the invention, in one aspect, accordingly provides a novel organization of mechanism for operating the gripper yieldingly to pull the upper heightwise of the last and for thereafter urging the gripper in the direction of the pull with less force than that applied in the upper-pulling operation. More particularly, the construction shown comprises a comparatively heavy spring through which updraw movement is imparted to the gripper, and a lighter spring for urging the gripper thereafter in the direction of the pull, together with automatic means for transferring the yielding control of the gripper from the heavy spring to the lighter spring after the updraw movement. Through the lighter spring the gripper is controlled in such manner that while it maintains a pull on the upper of sufficient force to prevent undesirable loss of tension, its overdraw movement may be readily effected and the overlaying operation may be performed without undue strain on the upper materials. Among other advantages, this arrangement permits the use of a heavier spring through which to effect the updraw movement of the gripper than would otherwise be practicable.

The novel features of the invention, in-

cluding various novel details of construction and combinations of parts, will now be more particularly described by reference to the accompanying drawings and pointed out in the claims.

5 In the drawings,

Fig. 1 is a view in right-hand side elevation of a portion of a machine in which the invention is embodied, parts of the structure being broken away;

10 Fig. 2 is a plan view of a portion of the structure shown in Fig. 1;

Fig. 3 shows in elevation a portion of the structure as viewed from the right-hand side of Fig. 1, parts being broken away;

15 Fig. 4 is a view similar to Fig. 1 of the upper portion of the structure there shown, with the parts in the positions that they occupy at the end of the upper-pulling operation;

20 Fig. 5 is a view similar to Fig. 4 with the parts in the positions that they occupy in the overlaying operation;

Fig. 6 is a view partly in plan and partly 25 in section of a portion of the structure shown in Fig. 2;

Fig. 7 is a view in left-hand side elevation, with the last and shoe shown in section, illustrating the positions of the gripper and of the overlaying member at the end 30 of the upper-pulling or updraw movement of the gripper; and

Fig. 8 is a view similar to Fig. 7, illustrating the positions of the parts at an intermediate stage in the overlaying operation.

35 The invention is herein illustrated as applied to a machine organization of the same general character as that fully disclosed in Letters Patent No. 1,796,451, granted on March 17, 1931, upon an application of 40 George Goddu, and only such parts of the machine, therefore, as it is necessary to refer to for an understanding of this invention are herein shown and will be described in detail.

45 It will be understood that machines of the type illustrated are so constructed as to last a shoe progressively by upper-pulling, overlaying and fastening operations performed successively in different locations along the 50 edge of the shoe bottom while the shoe is supported by the operator and is presented by him successively in different positions. To assist in positioning and controlling the shoe the machine is provided with a sole rest 10 (Figs. 7 and 8) which engages a sole or insole on the last and against which the operator supports the shoe. In operating upon a shoe provided with an insole having a lip or rib α on its outer face, as herein illustrated, the sole rest 10 is arranged to engage the inner face of the lip to assist in determining the position of the shoe and in holding it against displacement in a direction transverse to its height in the operation of 60 laying the upper inwardly over the insole.

For work of this kind the sole rest is so formed as to serve as an anvil for clinching the legs of staples driven through the upper and the lip of the insole to fasten the upper in lasted position. The upper is pulled in each lasting location by a gripper comprising a pair of jaws 12 and 14, the gripper being operated first to pull the upper heightwise of the last, as illustrated in Fig. 7, and thereafter to draw its marginal portion inwardly over the bottom of the last, these different movements of the gripper being commonly termed the updraw and overdraw movements. At the time when the gripper receives its overdraw movement an overlaying member 16 is advanced in a forwardly and downwardly inclined direction toward the outer face of the insole and by engagement with the tensioned marginal portion of the upper between the gripper and the edge 85 of the insole lays this portion of the upper over the outer face of the insole, as illustrated in Fig. 8, while the gripper continues its pull on the upper, this member continuing its movement until, in operating upon a shoe of the type illustrated, it presses the upper against the lip of the insole. When the member 16 has arrived substantially or nearly at the end of its operative movement the gripper is opened to release the upper. 90 Thereafter a staple is driven from the member 16 through the upper and the insole lip and is clinched on the sole rest member 10, as fully described in the above-mentioned Letters Patent.

100 As shown in Fig. 1, the gripper jaw 12 is fast on a holder 18 the upper end of which is clamped in a member 20 pivoted at 22 on the front end of a lever 24, this lever being mounted on a horizontal rock shaft 26 on the head of the machine. The gripper jaw 14 is supported on the holder 18 by a link 28 and is connected by a link 30 to a rod 32 through which it is moved toward and from the jaw 12 to grip and release the upper. The jaw 14 is held normally in releasing position by the lifting action of a spring 34 on the rod 32. To move the jaw into gripping position there is provided a rocking member 36 on the lever 24, this member engaging the upper end of the rod 32 and being engaged in turn by a thrust rod 38 slidably mounted in a boss 40 on the lever 24 and in an opening in the rock shaft 26. The rod 38 is operated by a lever 42 which is pivoted at 46 on the head of the machine, this lever being provided with a spring-controlled plunger 48 which abuts against the rear end of the rod 38. The lever 42 is provided with a roll 50 engaged and operated by a peripheral cam 52 on a cam wheel 54.

110 For imparting to the gripper its overdraw movement the machine is provided with an overdraw rod 56 mounted for sliding movement in a bracket 58 and pivotally connected 115

at its front end to a sleeve member 60 in which the gripper jaw holder 18 is slidably mounted. At its rear end the rod 56 is connected to one arm of a bell-crank lever 62 the other arm of which is provided with a roll 64 (Fig. 2) engaged by a peripheral cam 66 on the cam wheel 54. Connected to the bell-crank lever 62 is a torsion spring 68 which moves the lever in the direction to slide the rod 56 forwardly and thus to swing the gripper about its pivotal connection 22 with the lever 24 to draw the upper inwardly over the insole when the cam 66 permits this movement.

As thus far described the construction shown is substantially like that disclosed in the above-mentioned Letters Patent. Furthermore, in common also with the earlier disclosure, the means for operating the lever 24 to impart updraw movement to the gripper comprises another lever 70 which is pivotally mounted at 72 on the rear end of the lever 24 and is provided with a roll 74 (Fig. 2) engaged by a path cam 76 formed in one side of the cam wheel 54. For purposes of this invention, however, the connections between the lever 70 and the lever 24 for operating and controlling the latter are constructed differently from the disclosure of the prior Letters Patent. These connections comprise a member 78 provided with a vertical slot into which projects an upward extension of the lever 70, this member having fast on its front and rear ends, respectively, rods 80 and 82. The rod 80 extends through a sleeve member 84 which is threaded in an upward extension of the lever 24 and is provided with a knurled head 86 by which it may be adjusted, this head carrying a leather washer 87 against which the member 78 abuts. The rod 82 is surrounded by a coil spring 88 which presses at its rear end on a wing nut 90 on the rod and at its front end on the central portion of a yoke member 92 which is slidably movable on the rod and has arms 94 that extend forwardly in sliding contact with the opposite sides of the member 78. In their front ends the arms 94 are provided with curved recesses to receive the opposite end portions of a pin 96 fast in the upward extension of the lever 70, this pin extending through elongated slots 98 provided in the opposite side portions of the member 78. It will thus be seen that when the lever 70 is moved by the cam 76 in the direction to impart updraw movement to the gripper, the pin 96 imparts rearward movement to the yoke member 92 which acts through the spring 88 and the nut 90 on the rod 82 and the member 78. In order to transmit movement from the member 78 to the lever 24 there is provided means for connecting this member positively to the lever 24, this means comprising a latch 100 which is fast on a short rock shaft 102 mounted in depending ears on the

member 78 and hooks over the front face of the knurled head 86 on the sleeve member 84. The member 78 and the rods 80 and 82 are accordingly maintained in fixed relation to the lever 24 in the upper-pulling operation, this lever being operated through the spring 88 which yields more or less in response to resistance of the upper to the force of the pull thereon. It will be understood that the force of the pull may be varied by adjusting the nut 90. The positions of the several parts at the end of the updraw movement of the gripper are illustrated in Fig. 4.

In order to lessen the force tending to move the gripper heightwise of the last in the over-drawing and overlaying operations, the machine is further provided with means whereby the yielding control of the lever 24 is transferred from the spring 88 to a comparatively light spring 104 on the rod 80, this spring bearing at one end on a washer 106 in engagement with the upward extension of the lever 24 and at its opposite end on a nut 108 adjustable on the rod 80 to vary the compression of the spring. Such transfer is effected by moving the latch 100 into position to break the positive connection between the member 78 and the member 86. When this connection is broken the spring 88 impels the rod 82, the member 78 and the rod 80 rearwardly until the pin 96 on the lever 70 is seated at the left-hand end of the slots 98 in the member 78. By this movement of the rod 80 the spring 104 is compressed more or less, and this comparatively light spring serves thereafter as the yieldable means for controlling the gripper, the comparatively heavy spring 88 serving in effect as a rigid power-transmitting member. The positions of the parts under these conditions are illustrated in Fig. 5.

For operating the latch 100 to effect the result above described, the machine is provided with a bell-crank lever 110 mounted on the same pivot stud 46 as the lever 42. An upwardly extending arm of the lever 110 carries a screw 112 the end of which is arranged to bear on the front face of a depending arm 114 fast on the rock shaft 102 which carries the latch 100. This latch is held normally in position to connect the member 78 to the head 86 by a torsion spring 116 mounted on the shaft 102. The bell-crank lever 110 is controlled by a torsion spring 118 which is stronger than the spring 116 and tends to move the lever in the direction to withdraw the latch 100 from engagement with the head 86. To prevent this operation until the required time in the cycle, there is mounted on a rearwardly extending arm of the bell-crank lever 110 a member 120 which rests on the top of the roll 64 previously referred to as carried by the overdraw lever 62. It will thus be seen that at that time in the cycle when the cam 66 permits downward movement of the

130

roll 64 to render the lever 62 effective to impart to the gripper its overdraw movement the lowering of the roll 64 permits the spring 118 to swing the bell-crank lever 110 in a clockwise direction (Fig. 1) to withdraw the latch 100 from engagement with the head 86.

In the operation of the machine, briefly summarized, the gripper is operated to pull the upper heightwise of the last in each last-
10 ing location through the comparatively heavy spring 88 which transmits the force of the lever 70 to the lever 24 through the latch 100 connecting the member 78 to the member 86 on the lever 24. Substantially at the end
15 of the updraw movement of the gripper the cam 66 arrives in position to permit the roll 64 to be lowered and thus to render the overdraw spring 68 effective to swing the gripper jaws inwardly over the bottom of the last,
20 the overlaying member 16 at the same time being moved forwardly and downwardly toward the bottom of the shoe to lay the marginal portion of the upper over the insole.
At an early stage in the overdrawing opera-
25 tion, before the member 16 arrives in position to apply any substantial pressure to the upper, the lowering of the roll 64 results in such downward movement of the latch 100 as to disconnect the member 78 from the member
30 86. The spring 88 then instantaneously ex-
pands to the limit determined by the pin 96 and the slots 98, impelling the member 78 and the rod 80 rearwardly and compressing the comparatively light spring 104. Yielding
35 control of the lever 24 is thus transferred from the spring 88 to the spring 104, and during the remainder of the overdrawing operation of the gripper and in the overlaying operation of the member 16 the com-
40 paratively light spring 104 serves to urge the gripper heightwise of the last with less force than that applied through the spring 88 in the updraw movement of the gripper. The overdraw spring 68 is accordingly permitted
45 to force the gripper jaws well inwardly over the bottom of the last, and the member 16 performs the overlaying operation without undue strain on the upper, the gripper jaws being readily drawn toward the bottom of the
50 last against the resistance of the spring 104 by the pull of the upper thereon in this operation, so that they may be so controlled as to maintain their hold on the upper until
55 the member 16 has arrived substantially at the end of its operative movement. After these operations have been performed and after the upper has been fastened by driving a staple from the member 16 through the
60 upper and the insole lip, the parts of the machine are returned to their starting positions preparatory to the next cycle of operations. In such return of the parts the latch
100 is again connected to the member 86 for
65 transmitting the force of the spring 88 to

the lever 24 in the next updraw movement of the gripper.

It will be evident that, among other advantages of the invention, the avoidance of undue strain on the upper in the overdraw-
70 ing and overlaying operations, as above de-
scribed, facilitates control of the shoe by the operator and eliminates any danger that there may be, under some conditions, of distortion of the insole lip by the pressure of the sole rest 10 against its inner face. It will further be evident that the invention renders it practicable to use a stronger spring for imparting to the gripper its updraw move-
75 ment than if this spring remained in yield-
ing control of the upper in the overlaying operation, which is a substantial advantage in operating upon work in which the upper materials are comparatively heavy.

Having described the invention, what I claim as new and desire to secure by Letters Patent of the United States is:

1. In an upper-shaping machine, the combination with a gripper for pulling an upper over a last, and means for laying a portion of the upper inwardly over the bottom of the last, of mechanism for operating the gripper yieldingly to pull the upper, and additional mechanism for urging the gripper yieldingly in the direction of the pull with less force in the overlaying operation than that applied in the upper-pulling operation.

2. In an upper-shaping machine, the combination with a gripper for pulling an upper over a last, and means for laying a portion of the upper inwardly over the bottom of the last, of mechanism comprising a compara-
100 tively heavy spring for operating the gripper yieldingly to pull the upper, and additional mechanism comprising a lighter spring for urging the gripper in the direction of the pull with less force in the overlaying opera-
105 tion than that applied through said heavy spring in the upper-pulling operation.

3. In an upper-shaping machine, the combination with a gripper for pulling an upper over a last, and means for laying a portion of the upper inwardly over the bottom of the last, of mechanism for operating the gripper yieldingly to pull the upper, additional mechanism for urging the gripper yieldingly in the direction of the pull with less force in the overlaying operation than that applied in the upper-pulling operation, and automatic means for rendering said additional mechanism operative to control the gripper at a predetermined time in the operation of the machine.

4. In an upper-shaping machine, the combination with a gripper for pulling an upper over a last, and means for laying a portion of the upper inwardly over the bottom of the last, of mechanism comprising a compara-
115 tively heavy spring for operating the gripper yieldingly to pull the upper heightwise

of the last, a lighter spring arranged to urge the gripper in the direction of the pull with less force in the overlaying operation than that applied through said heavy spring in the upper-pulling operation, and means for transferring the yielding control of the gripper from said heavy spring to the lighter spring after the upper-pulling operation.

5. In an upper-shaping machine, the combination with a gripper for pulling an upper over a last, and means for laying a portion of the upper inwardly over the bottom of the last, of mechanism comprising a spring for operating the gripper yieldingly to pull the upper, another spring arranged to urge the gripper in the direction of the pull with less force in the overlaying operation than that applied in the upper-pulling operation, and means for rendering said other spring operative to control the gripper yieldingly in place of said first-named spring at a predetermined time in the operation of the machine.

6. In an upper-shaping machine, the combination with a gripper for pulling an upper over a last, and means for laying a portion of the upper inwardly over the bottom of the last, of mechanism for operating the gripper to pull the upper, said mechanism including members arranged in positive operative relation to each other, and means for establishing a yielding operative relation between said members at a predetermined time in the operation of the machine to urge the gripper in the direction of the pull with less force in the overlaying operation than that applied in the upper-pulling operation.

7. In an upper-shaping machine, the combination with a gripper for pulling an upper over a last, and means for laying a portion of the upper inwardly over the bottom of the last, of mechanism for operating the gripper to pull the upper, said mechanism including members connected to move in fixed relation to each other, means for interrupting the connection between said members to permit relative movement between them at a predetermined time in the operation of the machine, and a spring arranged to be subjected to stress by such relative movement and to urge the gripper in the direction of the pull with less force in the overlaying operation than that applied in the upper-pulling operation.

8. In an upper-shaping machine, the combination with a gripper for pulling an upper over a last, and means for laying a portion of the upper inwardly over the bottom of the last, of mechanism including a spring for operating the gripper yieldingly to pull the upper, said mechanism including also members connected to move in positive operative relation to each other, means for disconnecting said members to permit relative movement between them after the upper-pulling operation, and another spring arranged to be subjected to stress by such relative movement

and to urge the gripper in the direction of the pull with less force in the overlaying operation than that applied through said first-named spring in the upper-pulling operation.

9. In an upper-shaping machine, the combination with a gripper for pulling an upper over a last, and means for laying a portion of the upper inwardly over the bottom of the last, of a comparatively heavy spring through which to operate the gripper yieldingly to pull the upper heightwise of the last, members arranged to transmit the force of said spring to the gripper, a device for connecting said members positively together, means to cause said device to break the connection between said members and permit them to move relatively to each other at a predetermined time in the operation of the machine, and a comparatively light spring arranged to be subjected to stress by the relative movement of said members and to urge the gripper in the direction of the pull with less force in the overlaying operation than that applied through said heavy spring in the upper-pulling operation.

10. In an upper-shaping machine, the combination with a gripper mounted for updraw movement to pull an upper heightwise of a last and for overdraw movement to pull it inwardly over the bottom of the last, and means for imparting to the gripper said overdraw movement, of mechanism for imparting to the gripper yieldingly its updraw movement, and additional mechanism for urging the gripper yieldingly in the direction of its updraw movement with less force during its overdraw movement than that applied in its updraw movement.

11. In an upper-shaping machine, the combination with a gripper mounted for updraw movement to pull an upper heightwise of a last and for overdraw movement to pull it inwardly over the bottom of the last, and spring means for imparting to the gripper said overdraw movement, of mechanism comprising a comparatively heavy spring for imparting to the gripper yieldingly its updraw movement, a lighter spring arranged to urge the gripper yieldingly in the direction of its updraw movement during its overdraw movement, and automatic means for transferring the yielding control of the gripper from said heavy spring to the lighter spring.

12. In an upper-shaping machine, the combination with a gripper mounted for updraw movement to pull an upper heightwise of a last and for overdraw movement to pull it inwardly over the bottom of the last, overdraw means for imparting said last-named movement to the gripper, and means for laying the marginal portion of the upper inwardly over the bottom of the last, of mechanism for imparting to the gripper yieldingly its updraw movement, additional mechanism for urging

the gripper yieldingly in the direction of the pull with less force in the overlaying operation than that applied in its updraw movement, and a device controlled by said overdraw means for rendering said additional mechanism operative to control the gripper after its updraw movement.

13. In an upper-shaping machine, the combination with a gripper mounted for updraw movement to pull an upper heightwise of a last and for overdraw movement to pull it inwardly over the bottom of the last, overdraw means for imparting said last-named movement to the gripper, and means for laying the marginal portion of the upper inwardly over the bottom of the last, of mechanism comprising a comparatively heavy spring for imparting to the gripper yieldingly its updraw movement, a lighter spring arranged to urge the gripper in the direction of the pull with less force in the overlaying operation than that applied through said heavy spring in its updraw movement, and a device controlled by said overdraw means for transferring the yielding control of the gripper from said heavy spring to the lighter spring after the updraw movement of the gripper.

14. In an upper-shaping machine, the combination with a gripper for pulling an upper over a last, a lever for operating said gripper, and means for laying a portion of the upper inwardly over the bottom of the last, of mechanism comprising a spring for operating said lever yieldingly to pull the upper, and additional mechanism comprising another spring arranged to act on said lever to urge the gripper in the direction of the pull with less force in the overlaying operation than that applied through said first-named spring in the upper-pulling operation.

15. In an upper-shaping machine, the combination with a gripper for pulling an upper over a last, a lever for operating said gripper, and means for laying a portion of the upper inwardly over the bottom of the last, of mechanism comprising a comparatively heavy spring for operating said lever yieldingly to pull the upper, a lighter spring arranged to act on said lever to urge the gripper in the direction of the pull with less force in the overlaying operation than that applied through said heavy spring in the upper-pulling operation, and automatic means for transferring the yielding control of said lever from the heavy spring to the lighter spring at a predetermined time in the operation of the machine.

16. In an upper-shaping machine, the combination with a gripper for pulling an upper over a last, a lever for operating said gripper, and means for laying a portion of the upper inwardly over the bottom of the last, of mechanism comprising a spring for operating said lever yieldingly to pull the upper,

a member arranged to transmit the force of said spring to the lever, a device for connecting said member positively to the lever, means for breaking the positive connection between said member and the lever to permit the member to move relatively to the lever, and another spring arranged to transmit the force of said member to the lever when said connection is broken to urge the gripper in the direction of the pull with less force in the overlaying operation than that applied through said first-named spring in the upper-pulling operation.

17. In an upper-shaping machine, the combination with a gripper for pulling an upper over a last, a lever for operating said gripper, and means for laying a portion of the upper inwardly over the bottom of the last, of mechanism comprising a comparatively heavy spring for operating said lever yieldingly to pull the upper, a rod for transmitting the force of said spring to the lever, a latch for connecting said rod to the lever, means for operating said latch to release the rod and permit it to move relatively to the lever after the upper-pulling operation, and a comparatively light spring arranged to transmit the force of the rod to the lever when the rod is thus released to urge the gripper in the direction of the pull with less force in the overlaying operation than that applied through said heavy spring in the upper-pulling operation.

18. In an upper-shaping machine, the combination with a gripper for pulling an upper over a last, and means for laying a portion of the upper inwardly over the bottom of the last, of a lever connected to the gripper for operating it to pull the upper, another lever for operating said first-named lever, a spring connection between said levers for transmitting the force of one lever to the other in the upper-pulling operation, and an additional spring connection between the levers arranged to act with less force on the gripper in the overlaying operation than that applied in the upper-pulling operation.

19. In an upper-shaping machine, the combination with a gripper for pulling an upper over a last, and means for laying a portion of the upper inwardly over the bottom of the last, of a lever connected to the gripper for operating it to pull the upper, another lever for operating said first-named lever, a comparatively heavy spring for transmitting the force of one lever to the other in the upper-pulling operation, a lighter spring for transmitting the force of one lever to the other in the overlaying operation, and automatic means for rendering the lighter spring yieldable in place of the heavy spring.

20. In an upper-shaping machine, the combination with a gripper for pulling an upper over a last, and means for laying a portion of the upper inwardly over the bottom of the

last, of a lever connected to the gripper for operating it to pull the upper, another lever for operating said first-named lever, a spring and a rigid member for transmitting the force of one lever to the other in the upper-pulling operation, a positive connection between said member and one of the levers, and means for substituting a yielding connection for said positive connection to urge the gripper in the direction of the pull with less force in the overlaying operation than that applied in the upper-pulling operation.

21. In an upper-shaping machine, the combination with a gripper for pulling an upper over a last, and means for laying a portion of the upper inwardly over the bottom of the last, of a lever connected to the gripper for operating it to pull the upper, another lever for operating said first-named lever, a comparatively heavy spring and a rod for transmitting the force of one lever to the other in the upper-pulling operation, a device arranged to serve as a positive connection between said rod and one of the levers in that operation, means for breaking said positive connection after the upper-pulling operation, and a comparatively light spring arranged to serve thereafter as a yielding connection in place of said positive connection to urge the gripper in the direction of the pull with less force in the overlaying operation than that applied through the heavy spring in the upper-pulling operation.

22. In a machine for progressively lasting shoes, the combination with a gripper for pulling an upper over a last successively in different locations along the edge of the last bottom, means for laying a portion of the upper inwardly over a sole on the last after each upper-pulling operation of the gripper, and a sole rest arranged to engage the sole as the last and shoe are presented by the operator successively in different positions, of gripper-operating and controlling mechanism comprising a comparatively heavy spring arranged to act on the gripper yieldingly to pull the upper heightwise of the last and a lighter spring arranged to urge the gripper yieldingly in the direction of the pull with less force in the overlaying operation than that applied through said heavy spring in the upper-pulling operation.

23. In a machine for progressively lasting shoes, the combination with a gripper for pulling an upper over a last successively in different locations along the edge of the last bottom, means for laying a portion of the upper inwardly over a sole on the last after each upper-pulling operation of the gripper, and a sole rest arranged to engage the sole as the last and shoe are presented by the operator successively in different positions, of a lever for operating said gripper, mechanism comprising a comparatively heavy spring for operating said lever yield-

ingly to pull the upper heightwise of the last, a lighter spring arranged to act on said lever to urge the gripper in the direction of the pull with less force in the overlaying operation than that applied through said heavy spring in the upper-pulling operation, and automatic means for transferring the yielding control of said lever from the heavy spring to the lighter spring after the upper-pulling operation.

24. In a machine for progressively lasting shoes, the combination with a gripper for pulling an upper over a last successively in different locations along the edge of the last bottom, means for laying a portion of the upper inwardly over a sole on the last after each upper-pulling operation of the gripper, and a sole rest arranged to engage the sole as the last and shoe are presented by the operator successively in different positions, of a lever connected to the gripper for operating it to pull the upper, another lever for operating said first-named lever, a comparatively heavy spring for transmitting the force of one lever to the other in the upper-pulling operation, a lighter spring for transmitting the force of one lever to the other in the overlaying operation, and automatic means for rendering the lighter spring yieldable in place of the heavy spring.

25. In an upper-shaping machine, the combination with a gripper for pulling an upper over a last, of different springs each arranged to apply to the gripper force tending to move it heightwise of the last, and means for operating the gripper through one of said springs alone to pull the upper and for thereafter controlling it yieldingly through the other spring to hold the upper under tension.

26. In an upper-shaping machine, the combination with a gripper for pulling an upper over a last, of a comparatively heavy spring and a lighter spring each arranged to apply to the gripper force tending to move it heightwise of the last, and means for operating the gripper through said heavy spring to pull the upper and for thereafter controlling it yieldingly through the lighter spring to hold the upper under tension.

27. In an upper-shaping machine, the combination with a gripper for pulling an upper over a last, of mechanism including a spring for operating the gripper yieldingly to pull the upper, another spring arranged to urge the gripper yieldingly in the direction of the pull to hold the upper under tension, and means for rendering said other spring operative on the gripper after the upper-pulling operation.

28. In an upper-shaping machine, the combination with a gripper for pulling an upper over a last, of mechanism including a spring for operating the gripper yieldingly to pull the upper, another spring arranged to urge

the gripper yieldingly in the direction of the pull with less force than said first-named spring, and means for transferring the yielding control of the gripper to said other spring 5 at a predetermined time in the operation of the machine.

29. In an upper-shaping machine, the combination with a gripper for pulling an upper over a last, of a lever for operating said gripper to pull the upper, another lever for operating said first-named lever, different springs for transmitting the force of one lever to the other, and means to cause one of said springs to remain idle until force has 10 been applied to the upper through the other spring.

30. In an upper-shaping machine, the combination with a gripper for pulling an upper over a last, of a lever for operating said gripper to pull the upper, another lever for operating said first-named lever, different springs for transmitting the force of one lever to the other, and means to render one of said springs alone operative in the upper-pulling 20 operation and for thereafter transferring the yielding control of the gripper to the other spring to hold the upper under tension.

31. In an upper-shaping machine, the combination with a gripper for pulling an upper 30 over a last, of a lever for operating said gripper to pull the upper, another lever for operating said first-named lever, a comparatively heavy spring and a lighter spring for transmitting the force of one lever to the other, and means for rendering the heavy 35 spring operative in the upper pulling operation and for thereafter transferring the yielding control of the gripper to the lighter spring to hold the upper under tension.

40. 32. In an upper-shaping machine, the combination with a gripper for pulling an upper over a last, of a lever for operating said gripper to pull the upper, another lever for operating said first-named lever, a spring and a 45 rigid member for transmitting the force of one lever to the other in the upper-pulling operation, a positive connection between said member and one of the levers, and means for substituting a yielding connection for said positive connection at a predetermined time 50 in the operation of the machine.

55. 33. In an upper-shaping machine, the combination with a gripper for pulling an upper over a last, of a lever for operating said gripper to pull the upper, another lever for operating said first-named lever, a comparatively heavy spring and a rigid member for transmitting the force of one lever to the other in the upper-pulling operation, a device for 60 positively connecting said member to one of the levers, means to cause said device to disconnect said member and lever at a predetermined time in the operation of the machine, and a comparatively light spring arranged 65 to act thereafter in place of said connecting

device to hold the upper under tension with less force than that applied through said heavy spring in the upper-pulling operation.

In testimony whereof I have signed my name to this specification.

CHARLES A. ROBINSON.
